ART METAL CONSTRUCTION COMPANY, OF JAMESTOWN, NEW YORK

SUSPENSION FOR DRAWERS AND ANALOGOUS DEVICES

Application filed July 30, 1932. Serial No. 626,773.

This invention relates to that type of progressive or extensible suspensions or guide supports for drawers and other sliding devices, in which the sliding device is arranged to travel and is guided on an intermediate support or guide which, in turn, travels on a stationary guide so that when the drawer is pulled out, said travelling support will also move outwardly and properly guide the drawer and support it horizontally even when pulled out to substantially its full length. In this specification, for the sake of brevity and clarity, the sliding device will be called a drawer, but it is not thereby intended to limit the invention to use with drawers, since it is also adapted for supporting and guiding other sliding devices.

Metallic progressive suspensions of this sort commonly comprise a stationary track formed by channel or flanged bars located at opposite sides of the drawer and between which the drawer moves, drawer rails or bars fixed to the opposite sides of the drawer, and a travelling support including track bars interposed between and movable relatively to the drawer and stationary track bars, suitable rollers or the like being arranged to provide rolling anti-friction bearings between the drawer, intermediate and stationary tracks. In those progressive suspensions where the bearing rollers or elements are mounted on the intermediate support, which has been found to be a desirable arrangement, possessing certain recognized advantages, unless the devices are of relatively complicated and expensive constructions, the rollers are usually narrow and located so as to bear and throw the weight on restricted portions of one or another of the track bars at a distance laterally away from their points of anchorage, or the portions thereof which are fixed to the stationary support or drawer. This results in wear and the deformation of such track bars to such an extent as to interfere with the free, easy operation of the device and to materially shorten its life.

One object of this invention is to provide a progressive suspension of improved con-

struction which will overcome the above noted objections and will insure the free, easy movement of the drawer or sliding device which it supports. Other objects are to provide a desirable progressive suspension of relatively simple and economical construction which will be strong and durable and efficient in operation; also to construct suspensions of this type so that the rollers which largely support the weight of the drawer or load are disposed and formed so as to travel and bear on wider areas of the stationary tracks and closer to their points of attachment to their support and thereby reduce wear, prevent deformation of the stationary tracks and increase the life of the suspensions.

Further objects of the invention are to provide a stop device of improved construction for arresting the drawer at the end of its outward travel; and to produce a suspension device for drawers and other sliding devices which has the other features of improvement and advantage herein described and set forth in the claims.

In the accompanying drawings:

Fig. 1 is a fragmentary, longitudinal, sectional elevation of a metallic drawer cabinet or case provided with drawer suspensions embodying my invention.

Fig. 2 is a longitudinal, sectional elevation of one of the suspensions removed from the cabinet, the drawer rail being omitted.

Fig. 3 is a transverse sectional elevation on an enlarged scale on line 3—3, Fig. 1.

Fig. 4 is a fragmentary view similar to Fig. 2, but on a larger scale, and showing the inner end of the intermediate travelling support in its inner position.

Fig. 5 is a fragmentary perspective view of a portion of one of the track bars of the intermediate travelling support.

Fig. 6 is an enlarged, transverse sectional elevation through the suspension on the plane of line 6—6, Fig. 2.

A, Fig. 1, represents a portion of a drawer case or cabinet and B two drawers slidably mounted therein by means of drawer suspensions embodying my improvements. The case or cabinet and the drawers may be of

any usual or suitable construction, sheet metal case and drawers being shown in the drawings.

- As illustrated, the drawer suspension for 5 each drawer is built as a complete separate unit adapted to be placed and stationarily secured as such in the case or other stationary frame or support in which the drawer is to be mounted. This unit comprises a stationary track or guide formed by parallel rails or bars 10 disposed longitudinally at opposite sides of the drawer B and rigidly connected by transverse bars 11 which may be welded or otherwise rigidly attached to 10 the bars 10, preferably at their opposite ends; a pair of longitudinal drawer rails or bars 12 which are fixed by welding or otherwise to the opposite side walls of the drawer; and an intermediate, travelling 15 track or support comprising a pair of longitudinal rails arranged to travel between the drawer and stationary rails 10 and 12 at each side of the drawer. The opposite travelling support rails are preferably rigidly connected 20 so as to be retained in the intended parallel spaced relation, as by transverse end bars 14 welded or otherwise secured to the bars 13. The stationary track or guide may be stationarily secured in the cabinet A in 25 any suitable way, as for example, by means of lugs a and a' at opposite ends of the stationary rails 10 arranged to engage in slots a^2 and a^3 respectively in upright bars or parts a^4 of the cabinet.
- 30 Preferably, the stationary rails 10 are formed by metal channel bars having vertical webs and top and bottom flanges projecting from the webs inwardly towards the drawer; the drawer rails consist of metal angle bars 35 having vertical flanges welded or otherwise rigidly fastened to the opposite sides of the drawer and outwardly projecting bottom flanges; and the travelling support rails 13 consist of metal bars of substantially the 40 cross sectional Z-shape shown, having a transverse, horizontal web 15 and an upper flange 16 extending upwardly from the outer edge of the web 15 and a lower flange 17 extending downwardly from the inner edge 45 of the web 15. As shown, the lower flanges 17 have inturned or flanged lower edges 18 to which the transverse connecting bars 14 are attached.

Each rail 13 of the travelling support 55 preferably carries three lower rollers 19, 20 and 21 suitably journalled thereon and arranged to roll on the bottom flange of the adjacent stationary rail 10, the two pairs of rollers 19 and 21 being located respectively 60 at the outer and inner end portions of the travelling support, and the remaining pair of rollers 20 being located between the ends of the support in such a position as to be substantially half-way between the inner 65 and outer ends of the drawer when the latter

and the travelling support are in their innermost positions. In addition, each rail 13 of the travelling support is provided with an upper roller 22 at its inner end adapted to roll against the underface of the top flange of the companion stationary rail, and an upper roller 23 located above the middle, lower roller 20. The horizontal flanges of the drawer rails 12 extend between the lower and upper rollers of the travelling support and are adapted to bear downwardly on the lower rollers 19, 20 and 21, and upwardly against the upper rollers 22 and 23. The upper rollers 22 and 23 and the outer, lower rollers 19 are preferably provided with ball bearings by which they are mounted on the travelling support.

The lower middle rollers 20 in the construction shown turn freely about stud axles 24 rigidly secured to the lower flanges 17 of the travelling rails 13, and preferably the axle holes of the rollers are sufficiently larger than the axles 24 to permit some vertical play of the rollers 20 on their axles. The axles shown have enlarged outer ends seated in circular depressions 25 in the outer faces of the rollers 20 whereby the rollers are held on their axles. It will be noted that the lower rollers 19, 20 and 21 project through openings in the transverse web of the travelling rails 13 for engagement with the drawer rails 12 and that in the case of the middle, lower rollers 20, they are positioned so that their outer ends project outwardly to or beyond the outer faces of the upper flanges 16 of the rails 13 and substantially into contact with the inner faces of the vertical webs of the stationary rails 10, only the necessary running clearance being left between the vertical webs of the rails 10 and the rollers. To enable such positioning of the rollers, the upper flanges 16 as well as the transverse webs 15 of these travelling rails 13 are slotted or cut out for the passage of the rollers, as indicated at 26, (see Figs. 5 and 6). The rollers 20 can project outwardly beyond the rails 13 as far as will permit of a running clearance between the rollers and the webs of the stationary rails. Therefore, when thus located, the rollers 20 will bear at their outer edges on the lower flanges of the stationary rails in the closest possible relation to the vertical planes of the attaching or supporting webs or portions of the rails. This arrangement also permits the use of wider or longer rollers 20 having a wider bearing area on the faces of the rails on which they roll, thus resulting in longer life and less wear on the parts and preventing deflection or deformation of the lower flanges of the stationary rails, since the weight transmitted by the rollers to the rails is not confined to narrow paths near the free edges of the flanges or spaced from the webs or attaching portions of the rails,

but may be distributed over substantially the full width of the flanges.

In the operation of the device, when the drawer is in its inner or closed position, the 5 weight of the drawer and its contents will be more or less evenly distributed on the lower rollers of the travelling support. When the drawer is pulled out, the travelling support is caused to travel outwardly 10 therewith and at substantially half the speed of the drawer, by reason of the rolling engagement of the rollers with both the stationary rails and drawer rails. The overhanging weight of the drawer when pulled 15 out will tend to tip downwardly the projecting, outer end of the travelling support and raise the inner end thereof, thus placing the pressure downwardly on the outer and middle lower rollers and upwardly on the upper 20 per rollers of the travelling support. When the drawer has been pulled out to the limit, the middle, lower rollers 20 will be substantially at the outer end of the stationary track 10, and in the inward and outward 25 movement of the drawer, these rollers travel back and forth from this position to a position substantially midway between the ends of the stationary track. These middle, lower rollers 20, therefore, have to sustain a great 30 portion of the load and weight in the operation of the drawer and this they are much better able to do without serious wear and deformation of the stationary track rails, by reason of their greater width and disposition, as explained, so as to bear on the 35 flanges of the rails for practically their full width and close up to the fixed anchorage of these flanges.

As usual in suspensions of this sort, stop 40 devices are provided to arrest both the drawer and the travelling support at the intended limits of their outward movements. The stops for the travelling support may be of any usual or suitable construction, the 45 stops shown for this purpose consisting of dogs 30 pivoted between their ends on the upper, vertical flanges of the bars 13 with their front ends adapted to slide against the under sides of the upper flanges of the stationary rails 10. When the travelling support is pulled out nearly to its limit, the heavier, inner ends of the dogs 30 will throw the outer ends of the dogs up into slots 31 in the front ends of the upper 50 flanges of the rails so that the front ends of the dogs will strike the front edges 32 of these slots 31 and thus arrest the outward movement of the travelling support. The dogs can be swung on their pivots to clear 55 the stops 32 to permit the removal of the travelling support from the stationary track when this is desired.

The stops for limiting the outward movement of the drawer on the travelling support preferably consist of spring actuated 60

catches 33 pivoted at their inner ends on the upper flanges of the bars 13 and having upwardly projecting outer ends 34 which are normally held by the catch springs in the paths of fixed stops 35 on the opposite sides 70 of the drawer. As shown, the spring for each catch consists of a spring wire bent around the catch pivot with one end of the spring entering a hole in an inwardly projecting lug 37 on the adjacent bar 13 and the other end of the spring engaging a laterally offset portion 38 of the catch. The upward movement of the catch by the spring is limited by a projection 39 at the outer 75 end of the catch adapted to strike an inward lug on the outer end of the bar 13. Preferably the upper front edges of the upwardly projecting ends 34 of the catches are bevelled and the fixed stop plates 35 on the drawer are inclined forwardly and downwardly, as shown, so that when inserting the drawer into the suspension, these stops on the drawer will engage the bevelled ends of the catches and depress the catches and ride over them. When the drawer is pulled 80 outwardly, the front ends of the fixed stops 35 on the drawer will strike the projections 34 of the catches which will thus arrest the outward movement of the drawer. Preferably the rear edges of the catch projections 95 34 are notched as shown at 40, and the front edges of the drawer stops 35 are adapted to enter these notches and thus prevent the possibility of the drawer being accidentally lifted out of engagement with and passing 100 over the catches, in the normal outward movements of the drawer.

This drawer stop arrangement is adapted for use with drawers, such for example as tabulating card drawers, where the upper edges of the side walls of the drawer are substantially flush with the top of the front head, or the sides are substantially as deep as the drawer opening in the front of the cabinet. In such cases the drawer is not capable of sufficient vertical play in the drawer opening of the cabinet to allow a fixed stop on the drawer to ride or pass over a fixed stop on the travelling support when inserting the drawer into the cabinet. Therefore, fixed stops such as employed with drawers having low sides cannot be used. The depressible spring-actuated catches arranged at the front of the travelling support as described, do not require any vertical play 110 of the drawer in the cabinet for their operation.

I claim:

1. A suspension for drawers and analogous devices, comprising a stationary track, a movable track and an intermediate travelling track interposed between said stationary and movable tracks and movable relatively to both of them, and rollers carried by said intermediate track and arranged to roll 125 130

on said stationary and movable tracks, at least one of said rollers having a tread in rolling engagement with said first two mentioned tracks and extending laterally from 5 one of said tracks toward the other at least to the vertical plane of the portion of the intermediate track farthest removed laterally from said one track.

2. A suspension for drawers and analogous devices, comprising a stationary track, 10 a movable track and an intermediate travelling track movable relatively to both said stationary and movable tracks and having a vertical wall disposed and movable between 15 portions of said stationary and movable tracks at opposite sides of said vertical wall, rollers carried by said intermediate track and arranged to roll on said other tracks, at least one of said rollers having a tread in 20 rolling engagement with one of said first two mentioned tracks and extending laterally from said one track toward the other at least to the vertical plane of the face of said vertical wall farthest removed laterally from said 25 one track.

3. A suspension for drawers and analogous devices, comprising a stationary track, 30 a movable track and an intermediate travelling track movable relatively to both said stationary and movable tracks and having a vertical wall disposed and movable between 35 portions of said stationary and movable tracks at opposite sides of said vertical wall, rollers carried by said intermediate track and arranged to roll on said other tracks, at 40 least one of said rollers having a tread in rolling engagement with one of said first two mentioned tracks and extending laterally therefrom through said vertical wall to the side thereof away from said one track.

4. A suspension for drawers and analogous devices, comprising a stationary track, 45 a movable track and an intermediate travelling track interposed between said stationary and movable tracks and movable relatively to both of them, and rollers carried by said intermediate track and arranged to roll on said stationary and movable tracks, at least one of said rollers having a tread in 50 rolling engagement with said movable track and extending laterally therefrom toward said stationary track at least to the vertical plane of the portion of the intermediate track farthest removed laterally from said 55 movable track.

5. A suspension for drawers and analogous devices, comprising a stationary track, 60 a movable track and an intermediate travelling track movable relatively to both said stationary and movable tracks, said stationary track having a web and upper and lower flanges projecting laterally from said web respectively above and below said movable track, and said intermediate track having a 65 vertical wall disposed and movable between

said movable track and said web of said stationary track, and bearing rollers journalled on said intermediate track and arranged to roll on said movable track and the upper and lower flanges of said stationary track, 70 at least one of said rollers having a tread in rolling engagement with said movable track and extending therefrom to the opposite side of said vertical wall of the intermediate track for rolling engagement with one flange 75 of said stationary track in close proximity to the web of the stationary track.

6. A suspension for drawers and analogous devices, comprising a stationary track, 80 a movable track and an intermediate travelling track movable relatively to both said stationary and movable tracks, said stationary track having a web and upper and lower flanges projecting laterally from said web respectively above and below said movable track, and said intermediate track having connected upper and lower vertical flanges which are offset laterally relatively to each other, said upper flange being disposed and movable between said movable track and 85 said web of the stationary track, bearing rollers journalled on the upper flange of said intermediate track and arranged to roll on said movable track and on the bottom of the upper flange of the stationary track, and a 90 bearing roller journalled on the lower flange of the intermediate track and arranged to roll on the bottom of the movable track and on the lower flange of the stationary track, said last mentioned roller having a tread 95 extending from said movable track to the far side of said upper flange of the intermediate track.
